(57) **CLAIM**

The ornamental design for a cable management device, as shown and described.

DESCRIPTION

FIG. 1 illustrates a front view of the cable management device;
FIG. 2 illustrates a rear view of the cable management device;
FIG. 3 illustrates a top view of the cable management device;
FIG. 4 illustrates a bottom view of the cable management device;
FIG. 5 illustrates a right-side view of the cable management device, with the left side view a mirror image thereof;
FIG. 6 illustrates a top front perspective view of the cable management device;
FIG. 7 illustrates a bottom rear perspective view of the cable management device; and,
FIG. 8 illustrates a top right rear perspective view of the cable management device.
The broken lines form no part of the claimed design.
